ROBERT A. BONVENTURE, OF NEW YORK, N. Y.

TELEPHONE.

1,022,175.

Specification of Letters Patent.

Patented Apr. 2, 1912.

Application filed March 29, 1911. Serial No. 617,591.

To all whom it may concern:

Be it known that I, ROBERT A. BONVENTURE, a citizen of the United States, and residing at New York, in the county of New York and State of New York, have invented certain new and useful Improvements in Telephones, of which the following is a specification, such as will enable those skilled in the art to which it appertains to make 10 and use the same.

This invention relates to telephones and particularly to what are known as stand, desk or table telephones, and the object thereof is to provide an improved receiver attachment for telephones of this class whereby the necessity of holding the receiver to the ear by hand is avoided and whereby the wires of the receiver circuit are concealed or partially concealed and prevented from becoming twisted, tangled or formed into loops which frequently occurs in telephones of this class as usually constructed, a further object being to provide a receiver attachment of the class specified 20 which is composed of separate mechanical parts, part of which are movable and one of which consists of a rotary and vertically movable arm by which the receiver is supported, all of the parts being connected with 25 a telephone of the class specified without interfering, in any way, with the construction thereof, and with these and other objects in view, the invention consists in a receiver attachment for telephones of the class specified, constructed and operated in the manner hereinafter described.

The invention is fully disclosed in the following specification, of which the accompanying drawing forms a part, in which the 40 separate parts of my invention are designated by suitable reference characters in each of the views, and in which,—

Figure 1, is a front view of an ordinary telephone showing my improved receiver attachment applied thereto, part of the construction being in section;—Fig. 2, a view looking in the direction of the arrow 2 of Fig. 1 but showing only the top part of the main portion of the attachment and showing part of the construction in section;—Fig. 3, a partial section on the line 3—3 of Fig. 4;—Fig. 4, a plan view of the device as shown in Fig. 1 but showing the parts in a different position and on a reduced scale;—Fig. 5, a section on the line 5—5 of Fig. 1,

and Fig. 6, a section on the line 6—6 of Fig. 1 and on an enlarged scale.

In the drawing forming part of this specification, I have shown an ordinary stand or desk telephone comprising a standard *a*, 60 having a base *a*² and with the top of which the transmitter *a*³ is connected in the usual manner, and the standard *a* is provided with the usual receiver supporting arm *a*⁴ pivoted at *a*⁵ and having the usual receiver 65 yoke *a*⁶, and the pivoted end of which is provided with a downwardly directed finger *a*⁷ between which and the standard *a* is placed a spring *a*⁸, and said pivoted end of the arm *a*⁴ is also provided with the usual 70 upwardly directed and curved finger member *a*⁹ which passes into the standard *a* and operates in connection with the circuit making and breaking device *b*, said standard *a* being also provided with the usual transmitter circuit wires *b*², all of these parts being 75 of the usual construction.

In the practice of my invention, I detachably connect with the standard *a* a top arm *c* and bottom arm *c*² and the bottom arm *c*² is provided with a head *c*³ into which is screwed a receiver standard tube *d* which passes through a keeper *c*⁴ with which the arm *c* is provided. Secured in the top of the tube *d* is a tubular plug *d*² in which is 80 secured a supplemental tube *e*, and the tubular plug *d*² is provided at the top thereof with a flange or rim *d*³, and inclosing the supplemental tube *e* is a sleeve *f* in the lower end of which is secured a tubular plug *f*² 85 through which the supplemental tube *e* loosely passes, and the tubular plug *f*² is provided at its lower end with a flange or rim *f*³ which corresponds with the rim or flange *d*³ of the tubular plug *d*², and secured to the 90 flange or rim *f*³ of the tubular plug *f*² is a ring or band *f*⁴ which incloses the flange or rim *d*³ and which is provided with an inwardly directed flange or rim *f*⁵, and between the flanges or rims *d*³ and *f*³ of the 100 tubular plugs *d*² and *f*² is a ball race *f*⁶ and between the flange or rim *d*³ of the tubular plug *d*² and the flange or rim *f*⁵ is another ball race *f*⁷. As thus constructed it will be seen that the sleeve *f* is rotatable on the supplemental tube *e* which is stationary, and the top of the sleeve *f* is closed by a plug *g* having ears *g*² between which is pivoted a receiver arm *h*.

Within the top portion of the sleeve *f* the 110

supplemental tube *e* is provided with a spacing collar *e*² above which and in the annular space formed by the parts *e* and *f* is placed a spiral spring *e*³, one end of which is secured to the tube *e* at *e*⁴ and the other end of which is secured to the sleeve *f* at *e*⁵, and with this construction the sleeve or arm *h* is normally held in the position shown in Fig. 1 but when it is desired to use the receiver the said receiver arm is swung forwardly a quarter of a circle or approximately so as indicated in Fig. 4.

The receiver circuit wires *i* pass up through the receiver standard formed by the parts *d*, *e* and *f*, and pass out through the aperture *g*³ in the plug *g*, and are then passed through the receiver arm *h*, and connected with the receiver *h*² in the usual manner, and the receiver *h*² is preferably what is known as a "watch-case" receiver. The receiver arm *h* is provided with a head *h*³ which fits between the ears *g*² and the pivotal connection at *h*⁴ is such that the friction thereof will hold the arm *h* in any desired position of vertical adjustment but said arm need never be adjusted above the position shown in Fig. 1.

Secured to the head *h*³ of the arm *h* or to said arm adjacent to said head is a downwardly directed finger *j* which passes through a corresponding aperture *j*² in the plug *g*, and the stationary member *e* is provided in one side of its upper end with a recess *j*³ adapted to receive the finger *j*, and when the arm *h* has been rotated into the position shown in Fig. 4 a slight depression of said arm will force the lower end of the finger *j* into the recess *j*³ and the arm *h* will be locked in the position shown in Fig. 4, and the transmitting circuit in the standard *a* will be closed as hereinafter described.

Mounted on the arm *a*⁴ is a longitudinally ranging bolt *k* which is secured to said arm by a pin *k*², said bolt being provided, in the construction shown, with base flanges *k*³ and the outer end of the bolt *k* is provided, in the form of construction shown, with a head *k*⁴ movable in a spiral slot *k*⁵ formed in the sleeve *f*, and the head *k*⁴ of the bolt *k* preferably consists of a rotary anti-friction sleeve, and by means of this construction, when the arm *h* is swung into the position shown in Fig. 4, the arm *a*⁴ is raised and the circuit through the standard *a* is closed in the usual manner as will be readily understood.

From the foregoing description it will be seen that my receiver attachment does not in any way change the construction of the telephone as originally made and operated, my improvement consisting of separate parts detachably connected with the standard *a* and with the original receiver supporting arm *a*⁴ and whenever desired, or if desired at any time, my attachment may be removed

and the original telephone used in the usual manner, all that is necessary being to provide the arm *a*⁴ with the usual receiver.

The receiver *h*², as hereinbefore stated, is what is known as the "watch-case" receiver 70 and is held in place by a clamping device *h*⁵ which engages the body portion thereof and which consists of separate spring jaws connected at one end with a head *h*⁶ having a screw *h*⁷, and the opposite ends of which 75 are connected by a bolt or similar device *h*⁸, but my invention is not limited to any particular means for connecting the transmitter *h*² with the arm *h*.

As hereinbefore stated, in order to close 80 the circuit through the standard *a*, the arm *h* must be swung into the position shown in full lines in Fig. 4, and if it is desired, at any time, to discontinue the use of the telephone, for any purpose, without breaking 85 the circuit, all that is necessary is to depress the arm *h* when in said position so that the finger *j* will enter the recess *j*³ as shown in Fig. 3, and this will lock said arm in the position shown in full lines in Fig. 4. 90

Although I have shown and described the preferred form of my improvement, my invention is not limited to the exact construction, combination and arrangement of the parts herein shown and described, and various changes therein and modifications thereof may be made, within the scope of the appended claims, without departing from the spirit of my invention or sacrificing its advantages. 95

Having fully described my invention, what I claim as new, and desire to secure by Letters Patent, is:—

1. In a telephone, the combination with the standard of the transmitter having the usual pivoted receiver supporting arm and the usual circuit wires which pass therethrough of a receiver supporting attachment comprising a tube adapted to be secured to the standard of the transmitter below said arm and terminating below said arm and provided with an extension of less diameter, and which passes upwardly through the fork of said arm, a rotary sleeve mounted on said extension and also passing through said fork, a tension device for holding said rotary sleeve in a predetermined position, a supplemental receiver arm pivoted to the top of the rotary sleeve and adapted to turn therewith and to swing vertically, means operated by swinging the supplemental receiver arm vertically to lock the rotary sleeve in a predetermined position, and means whereby the rotary movement of said arm and sleeve will operate the first named receiver arm to close the circuit through the standard of the transmitter. 110

2. In a telephone, the combination with the standard of the transmitter having the usual pivoted receiver supporting arm and 130

the usual circuit wires which pass therethrough, of a receiver supporting attachment comprising a tube adapted to be secured to the standard of the transmitter below said arm and terminating below said arm and provided with an extension of less diameter, and which passes upwardly through the fork of said arm, a rotary sleeve mounted on said extension and also passing through said fork, a tension device for holding said rotary sleeve in a predetermined position, a supplemental receiver arm pivoted to the top of the rotary sleeve and adapted to turn therewith and to swing vertically, means operated by swinging the supplemental receiver arm vertically to lock the rotary sleeve in a predetermined position,

and means whereby the rotary movement of said arm and sleeve will operate the first named receiver arm to close the circuit through the standard of the transmitter, and said tube and its extension and the supplemental receiver arm being also provided with receiver circuit wires which are passed therethrough.

25

In testimony that I claim the foregoing as my invention I have signed my name in presence of the subscribing witnesses this 28th day of March 1911.

ROBERT A. BONVENTURE.
